UNITED STATES PATENT OFFICE

156,061

DESIGN FOR A WATCH CROWN

Joseph Waldman, Maplewood, N. J.

Application November 22, 1948, Serial No. 149,750

Term of patent 3½ years

(Cl. D42—1)

To all whom it may concern:

Be it known that I, Joseph Waldman, a citizen of the United States, residing at Maplewood, county of Essex, and State of New Jersey, have invented a new, original, and ornamental Design for a Watch Crown, of which the following is a specification, reference being had to the accompanying drawings, forming part thereof.

In said drawings:

Fig. 1 is a top plan view of a watch crown, showing my new design;

Fig. 2 is a side elevational view of the same; and

Fig. 3 is a bottom plan view of the same.

I claim:

The ornamental design for a watch crown, as shown.

JOSEPH WALDMAN.
